WIRING DEVICE

Charles E. Rutherford, West Hartford, Conn., assignor to The Wiremold Company, Hartford, Conn., a corporation of Connecticut

Application May 23, 1935, Serial No. 22,960

2 Claims. (Cl. 247—15)

My invention relates to wiring devices; particularly to means by which wiring devices may be conveniently and quickly installed, as well as rigidly held in place after installation. It is particularly useful where it is necessary to install a wiring device against the side of a wall, molding or other obstruction, but its utility is not limited to such cases. The particular character of the wiring device, whether switch, junction box, outlet or other, is immaterial.

In the drawing attached hereto

Fig. 1 is an exploded view showing the three main elements of my wiring device;

Fig. 2 is a view showing the under side of the central member;

Fig. 3 shows the underside of the base plate;

Fig. 4 is a longitudinal section of the device assembled in place;

Fig. 5 is a view similar to Fig. 4, but showing a modified form;

Fig. 6 is a view of the base plate of the modified form shown in Fig. 5;

Fig. 7 is a section on the line 7—7 of Fig. 5;

Fig. 8 shows the device of Fig. 5, in plan, at the time of installation.

Fig. 9 is a view of a modified form of base plate.

In Fig. 1, which illustrates my invention as applied to a snap switch such as is used in household wiring, 10 is the porcelain body of the switch, provided with screws 11, 11, for attaching wires, with a top plate 12, provided with a rectangular slot 12a, through which the operating handle 13 protrudes. The porcelain body 10 is provided on its lower side with a recess 14 (Figs. 2 and 4) in which is mounted the metal strap 15. Screws 16, 16, pass through this strap and engage with threaded holes 16a, 16a, in the top plate 12.

The ends of the strap piece 15 are bent down and shaped to provide projecting lugs 16', as shown in Figs. 2 and 4.

The base plate 17, shown in Fig. 1, is provided with holes 17a, 17a, 17a, by which it may be screwed in place, as for example on a wall, and with lugs 18, one of which is shown at 19 as having been broken or cut off. It also is provided with slots 20, which are shown as being cut in a portion of the base plate 17 which is bent up above its general level.

The device shown in Figs. 5, 6, 7 and 8 is one which is so shaped as to allow a central screw 21 to be used to hold the parts together; the particular device shown is a double receptacle, each side capable of holding and connecting to the electrical current one attaching plug, as is well known in the art. The central screw 21 engages with a

threaded opening in a boss 22, which is located in the base plate.

In this form, in place of the bent lugs 16 of the first form I use headed studs, 23, 23, which are molded into the main body 10 of the receptacle. Between these studs and the main body of the receptacle I provide an insulating plate 24, which is kept in place by the studs, being provided with holes through which the studs pass. The length of the studs is such as not only to allow room for the plate 24, but also to allow room for the studs to pass into the slots 20, 20, of the base plate, as shown in Fig. 5.

The construction of the molded body and its relation to the plate 24 and the studs 23 appear in Fig. 7.

In Fig. 9 I show an alternative form of base plate, in which the holes 20a, 20a, are modified with special reference to securely holding the bent up lugs 16 of Fig. 2.

In each form the cover member 27 is provided with knock-out openings 25; in the upper part of Fig. 1 one of these openings, 25a, is shown at each end as knocked out.

To install the device it is necessary first to attach the base plate 17 in its permanent location, as by screws passing through the holes 17a. The wires 26, 26, Figs. 4 and 8, are then connected to the screws 11, 11, and the member 10 is temporarily installed in place by slipping the two lugs or studs, 16 or 23 as the case may be, into the two holes 20, 20, of the base plate, and rotating the member 10 through a small arc until the lugs or studs assume the position in the holes which is shown in Fig. 3, with the projecting ends of the lugs or studs extending behind the adjacent portions of the base plate. It will appear from Fig. 8 that this operation can be performed when the base plate 17 is installed so as to touch a side wall, molding or base board 28.

There is enough frictional engagement between the lugs or studs and the holes 20 to retain the member 10 in place until the time comes to apply the cover member 27. The arrangement is such that the cover member, when applied, holds all of the parts rigidly in place.

In the first form shown the cover member is held in place by two screws, 29, 29, which engage with the threaded holes 30, 30, in the top plate 12, Figs. 1 and 4. In the second form the screw 21 passes through a hole in the cover member, and engages the stud 22 described above, as shown in Fig. 5.

In both cases the result is to lock the cover plate in a position in which the lower walls of

the cover member pass down over the base plate, in such a way as to hold the cover member from rotating, and lock everything securely together in place, this action being aided by the projections 24 from the base plate, where such projections are present. Rotation of the main member 10 is prevented by the engagement of the switch handle 12 with the slot 12a in which it works, or by some similar engagement of the parts; for example in the modified form shown in Figs. 5, 6, 7 and 8, the upper projecting flanges 32, 32, of the molded body portion 19 of the receptacle engage with openings in the cover member 27, as shown in Fig. 5, so that so long as the cover member is held in place the molded member cannot rotate.

To adapt my invention to use with any type of conduit, wiring raceway or similar device it is only necessary to give the proper shape to the knock-out openings 25. The particular shape of these knock-out openings shown in the drawing is suitable for use with the type of conduit known to the trade as Wiremold, one form of which is shown in Murphy Patent No. 1,981,742. This form of conduit is particularly adapted to be fastened in place by slipping it on to one of the projecting tongues 18 as shown at 31 at the left of the lower part of Fig. 1. Such of the tongues as are not used are removed by breaking or cutting off, in the usual way, as shown at 19. When the cover is applied in place, the knocked out opening 25a of the cover plate embraces the conduit, affording an additional means of locking the whole structure permanently in place, the cover member being secured against rotation by

its attachment to the conduit members as well as by its engagement with the base plate or portions struck up therefrom.

I claim:

1. In a wiring device, two members, one of which is a base plate and one a body portion, means for fastening the base plate in its desired location, rigid projecting means on one of the said members adapted to project behind portions of the other member by a slight movement of the body portion in part in a direction parallel to said base plate, a cover member and means for fastening the cover member rigidly in place with relation to the base plate, the cover member being shaped to engage with the body portion in such a manner as to prevent the body portion from being so moved in a direction parallel to said base plate as to be disengaged from the base member when the cover member is in position.

2. In a wiring device, two members, one of which is a base plate and one a body portion, means for fastening the base plate in its desired location, rigid projecting means on one of the said members adapted to project behind portions of the other member by a slight rotational movement in a direction parallel to said base plate; a cover member and means for fastening the cover member rigidly in place with relation to the base plate, the cover member being shaped to engage with the body portion in such a manner as to prevent the body portion from being so rotated as to be disengaged from the base member when the cover member is in position.

CHARLES E. RUTHERFORD. 35
